UNITED STATES PATENT OFFICE.

CYRUS B. KURTZ, OF CLEVELAND, OHIO.

BUCKLE.

1,050,470.

Specification of Letters Patent.

Patented Jan. 14, 1913.

Application filed May 12, 1911. Serial No. 626,838.

To all whom it may concern:

Be it known that I, CYRUS B. KURTZ, of Cleveland, Cuyahoga county, Ohio, have invented a new and useful Improvement in 5 Buckles, of which the following is a full, clear, and exact description, reference being had to the accompanying drawings, forming part of this specification, in which—

10 Figure 1 is a plan view of my improved buckle, with straps applied thereto; Fig. 2 is a side view of the same; Fig. 3 is a bottom plan view with one of the straps shown in dotted lines; and Fig. 4 is a longitudinal 15 section of the buckle, with the straps removed and the bail member shown as swung downwardly in full lines.

My invention has relation to buckles, and while used for a variety of purposes, has 20 been more particularly designed as a buckle for automobile top straps.

The object of my invention is to provide a simple and efficient buckle of this character which can be readily manufactured.

25 A further object of the invention is to provide a buckle having means by which a strap can be drawn tighter than is possible with the ordinary buckle.

My improved buckle comprises a frame 30 composed of the two side bars 2, which are connected at one end by the end bar 3, and also have an intermediate connection by a cross bar 4, on which is pivoted the tongue 5. The side bars 2 are shown as narrowed 35 inwardly beyond the cross-bar 4 so as to reduce the width of the frame at this end portion. The side bars 2 are connected at the opposite end by a guard loop 6, which is raised above the plane of the side bars. Below 40 this guard loop 6, the side bars are extended downwardly to form lugs or ears 7, to which is pivotally connected a bail member, which consists of side arms 8, end connecting bar 9, and an intermediate bar 10.

45 The side bars 8 are arranged to move upwardly between the side bars 2 of the main frame, and the end bar 9 is offset upwardly above the plane of the side bars 8. Each of the side bars 8 also has a stop flange or lug 50 0 11 which prevents the bail from moving beyond a position slightly past the central plane of the main buckle frame.

12 designates the upper strap, and 13 the lower strap. The strap 12 is inserted 55 through the loop of the main frame between the bars 3 and 4, and is engaged with the

tongue 5. Its end is then passed underneath the end bar 9 of the bail member, and also underneath the guard bar 6 of the main frame. The strap 13 is formed with a loop 60 14, which is engaged with the cross-bar 10 of the bail member. It will be readily seen that the pull or tension on the straps will cause the upper strap 12 to be tightly clamped by the action of the bail member, 65 which tends to press said strap downwardly between the side bars of the main frame and effectively prevents the strap being thrown out of position by the vibration of the vehicle. When the buckle is applied to the 70 strap the strap 12 is passed under the front bar 3 and the tongue 5 is inserted through one of the holes. The bail is then swung under the plane of the buckle and up into position to receive the end of the strap 12. 75

With the ordinary buckle through which a strap is pulled and then fastened by inserting a tongue in a hole of the strap, the entire slack of the strap can not be taken up, owing to the bend of the strap over the 80 bar of the buckle. My improved buckle enables substantially all of the slack to be taken up, since after the tongue is engaged with the strap in the usual manner, the movement of the bail, as described, takes up 85 all looseness and makes the strap perfectly tight.

I do not desire to limit myself to the precise construction shown, as it is obvious that various changes can be made in the details 90 of construction and arrangement of parts, without departing from the spirit and scope of my invention as defined in the appended claims.

What I claim is:—

1. The herein described buckle, comprising a frame having a tongue bar and a tongue carried by said bar, a loop at the opposite end of the frame from the tongue bar, a bail member pivoted to the frame adjacent to said loop and having a transverse strap-attaching member, said bail member being capable of swinging forwardly and upwardly between the side members of the frame, and a loop at the front end of said 100 bail member arranged to lie above the plane of the buckle frame; substantially as described.

2. The herein described buckle, comprising a frame having a tongue bar near the 110 front end thereof and a tongue carried by said bar, a cross bar connecting the frame in

front of the tongue bar, a loop connected to the rear end of the frame and lying in a plane above the plane in which the tongue bar and the bar connecting the front end of the frame lie, a bail member pivoted to the rear end of the frame below the loop and lying between the side members of the frame, a transverse strap-attaching bar on the bail between its ends, a loop at one end of said bail lying in the same plane as the loop on the frame when the bail is swung

upwardly, and stops on the bottom of the bail for engaging the side members of the buckle frame when said bail is swung into position; substantially as described.

15

In testimony whereof, I have hereunto set my hand.

CYRUS B. KURTZ.
